Fig 9

FIG. 1 is a carrying case for high fidelity equipment or similar articles showing my new design;

FIG. 2 is a side elevational view taken from the right of FIG. 1;

FIG. 3 is a rear elevational view thereof;

FIG. 4 is a side elevational view taken from the left of FIG. 1;

FIG. 5 is a top plan view thereof;

FIG. 6 is a bottom plan view thereof;

FIG. 7 is a perspective view thereof;

FIG. 8 is a perspective view of the design in an open position;

FIG. 9 is a front elevational view thereof.

I claim:

The ornamental design for a carrying case for high fidelity equipment or similar articles, substantially as shown and described.
